UNITED STATES PATENT OFFICE.

JOHN SCHUT, OF CHICAGO, ILLINOIS.

POCKET COIN-RECEPTACLE.

1,159,535.

Specification of Letters Patent.

Patented Nov. 9, 1915.

Application filed May 13, 1914. Serial No. 838,348.

To all whom it may concern:

Be it known that I, JOHN SCHUT, citizen of the United States, residing at Chicago, in the county of Cook and State of Illinois, have invented certain new and useful Improvements in Pocket Coin-Receptacles, of which the following is a specification.

This invention relates to pocket coin receptacles, and has as its object to provide a device of this class adapted to contain a maximum number of coins of the same denomination, for example five-cent pieces, and to be capable of operation to discharge the coins one at a time.

15 The invention is designed more especially for use by persons who have occasion to ride frequently in "pay-as-you-enter" cars where it is desirable to have at hand the exact fare.

One feature of the invention resides in so 20 constructing the device that it may be manipulated with one hand to discharge the coin and may be held over the fare box or in position to discharge the coin into the conductor's hand.

25 Incidentally the invention contemplates a construction in which the device may be actuated readily and conveniently even if the user is at the time wearing gloves.

Another aim of the invention is to so construct the actuating means that it will not be liable to be accidentally operated by coming into contact with clothing or the lining of the pocket in which it is carried.

Further the invention aims to provide a 35 device of this class which will be simple in construction and so compact as to permit of its being carried in the pocket in the same manner as a watch.

In the accompanying drawings: Figure 1 40 is a perspective view of the coin receptacle embodying the present invention; Fig. 2 is a vertical transverse sectional view therethrough; Fig. 3 is a sectional view taken in a plane at right angles to the plane of the section of Fig. 2; and Fig. 4 is a perspective view of the coin holding and ejecting disk.

In the drawings, the device is illustrated as including a casing preferably comprising two counter-part sections, indicated by the numeral 1, connected in any suitable manner, either permanently or detachably, and provided at its upper side with a ring 2 whereby the casing may be connected with a chain or the like.

55 In order to permit of the coins contained

within the receptacle being discharged therefrom, in a manner which will be presently explained, one of the sections of the casing at its lower side has its rim cut away or recessed as at 3, and the other section has 60 its rim and a portion of its face cut-away as indicated at 4. The recess 3 of the first-mentioned section extends only to the margin of the face of said section, while, as stated, the recess 4 is formed not only in the rim but also in the face of the section, and the purpose of this construction will be presently pointed out.

The coin holding and ejecting disk, mentioned above, is indicated by the numeral 5 and is rotatably mounted upon a short shaft 6 secured at its ends in openings 7 in the sections 1 of the casing. Not only are the coins contained within the receptacle intended to be discharged through the opening 75 formed by the matching recesses 3 and 4, but they are also to be inserted into the receptacle through the said opening.

In order that pockets may be provided for the reception of the coins, the disk 5 is formed 80 with radial slots 8 and the material between the walls of the slots is stamped to form radially extending flanges 9 which alternately project from opposite faces of the said disk, in the manner clearly shown in 85 Fig. 4 of the drawings. In other words, each side of the disk 5 is provided with a set of flanges 9, the set of flanges upon one side of the disk being disposed in staggered relation to the set of flanges upon the other 90 side thereof. These flanges may project at right angles from the faces of the disk, or at any other desired angle, but in any event they are so proportioned that their longitudinal edges will be located close to the 95 inner faces of the casing sections 1 so that coins inserted within the receptacle will not be likely to become wedged between the edges of the flanges and the said flanges of the casing sections. At this point it may 100 be stated that coins are to be inserted alternately at opposite sides of the disk 5, or in other words one coin is to be inserted between one face of this disk and the opposing casing section, and the next coin inserted is to be disposed between the other face of the said disk and the other casing section.

As a means for successively bringing the coins into position opposite the opening 110

formed by the recesses 3 and 4, a spring 10 is secured at one end to the shaft 6 and at its other end, as at 11, to one face of the disk 5 and is adapted to be tensioned when the disk is rotated in one direction and when relieved of tension to rotate the disk in an opposite direction. This tensioning of the spring is accomplished by rotating the disk in the first-mentioned direction as the coins 10 are successively inserted into the casing, and means which will now be described, is provided for holding the disk against backward rotation but is capable of actuation to allow the disk to rotate in a step by step 15 manner to successively discharge the coins.

The means above-mentioned consists of two pawls which are arranged to coöperate with ratchet teeth formed at the periphery of the disk. The ratchet teeth are indicated 20 by the numeral 12 and correspond in number to the flanges 9 so that, as the disk rotates the distance of one tooth, two adjacent ones of the flanges 9 at one side or the other of the disk will be brought into position 25 opposite the opening in the lower side of the casing, or in other words substantially to the position shown in Fig. 2 of the drawings.

In order to accommodate the pawls above-mentioned, the casing is bulged, preferably at opposite sides as indicated at 13, and fixed within each bulged portion of the casing is a short shaft or pin 14 upon which the pawl, indicated in general by the numeral 15, is mounted for rocking movement. Each pawl has a finger 16 projecting in one direction from the pin 14 and provided at its extremity with a tooth 17 arranged to engage against the abrupt faces of the 40 ratchet teeth 12. A detent finger 18 projects in an opposite direction from the pin 14 and is arranged to perform a function to be presently stated. The finger 18 of each pawl carries a finger button 19, the shank 45 of which projects through a slot 20 formed in the respective bulged portions of the casing. In order to hold each pawl in position for coöperation with the ratchet teeth 17, leaf springs 21 are secured within the casing and rest at their free ends against the 50 fingers 16 in the manner shown in Fig. 2 of the drawings.

In filling the receptacle with coins, the coins are alternately inserted at opposite 55 sides of the disk 5 in the manner heretofore explained, and as each coin is inserted the disk is rotated backwardly a distance equal to the length of one of the ratchet teeth 12. Such rotative movement of the disk will result in the winding up of the spring 10, as will be readily understood. When it is desired 60 to discharge a coin from the receptacle, the finger buttons 19 of the two pawls are simultaneously pressed inwardly, thereby moving 65 the teeth of the pawls out of engagement

with the ratchet teeth of the disk. Such movement of the pawls will bring their fingers 18 into position to form abutments for the next adjacent ratchet teeth 12, and upon release of the finger buttons the fingers 18 70 will be moved through the action of the springs 21 out of engagement with the ratchet teeth, and the fingers 16 will be returned to their normal position and the teeth which have previously been in engagement with the ends of the fingers 18 will then rest in engagement with the teeth 17 of the pawls. It will be understood, of course, that during this manipulation of the finger buttons, the disk 5 will have been rotated a distance equal to the length of one of the ratchet teeth and the coin, which will then be in the position occupied by the coin 80 a in Fig. 2, will be permitted to drop through the opening in the bottom of the casing. 85

It will be apparent that by providing two of the pawls there is little likelihood of the finger buttons being accidentally pressed inwardly simultaneously by engagement with the lining of the pocket in which the device 90 is carried, and inasmuch as pressure against a single one of the buttons will not release a coin, loss of coins contained within the receptacle is not likely to result from ordinary use or handling of the device. 95

It will be understood, of course, that inasmuch as the recess 4 extends into the face of the section in which it is formed, coins may be readily introduced into the receptacle and the coin carrying disk may be 100 readily rotated. It is preferable that a numeral be marked upon each tooth 12, as clearly shown in Figs. 2 and 4 of the drawings, so that the user of the device may tell at a glance the number of coins contained 105 within the receptacle.

Having thus described the invention, what is claimed as new is:—

1. A device of the class described, including a casing, a coin holding disk rotatably mounted in the casing, outstruck coin confining flanges projecting alternately from the plane of the body of the disk upon opposite sides thereof, the casing having an outlet for the coins, means arranged to rotate the disk to successively bring the coins carried thereby into position for discharge through the outlet, and means normally restraining the disk against rotative movement and operable to release the disk for step by step rotative movement. 110

2. In a device of the class described, a casing, a coin carrier arranged within the casing, the casing being provided with a coin outlet, and the carrier being movable to successively bring the coins to position for discharge through the outlet, and means normally restraining the carrier from such movement and including elements each provided with a finger piece projecting exte- 115 120 125 130

riorly of the casing and arranged, when simultaneously actuated by said finger pieces, to release the carrier for such movement.

3. A device of the character described including a casing having a coin outlet, a coin carrying disk mounted for rotation within the casing and provided with ratchet teeth, said disk being formed with coin receiving pockets alternated at opposite sides of the 10 disk, means for rotating the disk in one direction whereby to successively bring the coins into position for discharge through the outlet, a pawl mounted in the casing and having a tooth normally coöperating with 15 the ratchet teeth to hold the disk against such movement, the said pawl having a finger arranged to constitute an abutment for engagement by one of the teeth upon disengagement of the tooth of the pawl from the 20 ratchet, and a leaf spring secured at one end to the casing and having its opposite end engaging the pawl to return the pawl to normal position upon movement to bring the 25 said finger into operative position and release the disk for such movement.

4. A device of the character described including a casing, a coin holding disk rotatably mounted in the casing, a set of outstruck radially disposed coin confining

flanges projecting laterally from each side 30 of the disk, the set upon one side of the disk being disposed in staggered relation to the set upon the other side of the disk, said casing being provided with an outlet for the coins, means arranged to rotate the disk to 35 successively bring the coins carried thereby into position for discharge through the outlet, and means normally restraining the disk against rotative movement.

5. A device of the character described including a casing having a coin outlet, a coin holding disk rotatably mounted in the casing, outstruck coin confining flanges projecting laterally from opposite sides of the disk, adjacent flanges upon each side of the 45 disk providing a coin receiving pocket disposed laterally upon one side of the plane of the body of the disk, and means arranged to rotate the disk to successively bring the coins carried thereby in position for discharge 50 through the outlet.

In testimony whereof I affix my signature in presence of two witnesses.

JOHN SCHUT. [L.S.]
